UNITED STATES PATENT OFFICE.

JOSEPH RABER, OF POPLAR BLUFF, MISSOURI, ASSIGNOR TO DALTON ADDING MACHINE COMPANY, OF ST. LOUIS, MISSOURI, A CORPORATION OF MISSOURI.

ESCAPEMENT FOR TYPE-WRITERS AND RECORDING-MACHINES.

1,005,783.

Specification of Letters Patent. Patented Oct. 10, 1911.

Application filed February 1, 1909. Serial No. 475,402.

To all whom it may concern:

Be it known that I, JOSEPH RABER, a citizen of the United States, residing at Poplar Bluff, Missouri, have invented new and useful Escapements for Type-Writers and Recording-Machines, of which the following is a specification.

This invention relates to escapements for typewriting and other recording machines wherein a lateral step by step movement is imparted the paper carriage during the operation of the machine.

In a companion application filed on even date herewith, Serial No. 475,403 I have described a mechanism embodying two escapement pawls which are operable across the path of the escapement wheel. In this application, therefore, it is unnecessary to describe the construction, arrangement and operation of the pawls and other supports since they are mounted and operated substantially the same as set forth in the said application above referred to.

The subject matter of this invention includes an adjustable stop or abutment whereby the operation of the escapement pawls across the escapement wheel is controlled.

This invention includes also certain improvements in the arrangement of the escapement shaft and the rocker supporting the escapement pawls.

In the accompanying drawings Figure 1 is an end elevation of the escapement mechanism embodying my present invention. Fig. 2 is a side elevation thereof, partially in section, illustrating the arrangement of the escapement shaft. Fig. 3 is a perspective view of the adjustable stop and rocker.

As in the companion application referred to, the support or hanger 1 is arranged for adjustment to the machine in suitable position and is provided at its upper extremity with bearings 2 adapted to receive the escapement shaft 3. The bearings in this instance comprise annular flanges 4 within which are located the rings 5 having at their inner ends the inclined shoulders 6 constituting the walls of race-ways for the balls of which the bearings are formed. At one end of the shaft 3 a pinion 7 is attached adapted for engagement with the rack on the paper carriage in the usual manner. A hub 8 rigid with said pinion is provided with a beveled end as shown at 9, the smaller

portion of the hub extending into the ring 5 and together with said ring holding the balls 10 in position therein, said balls constituting the only support for this end of the shaft. At the opposite end of the shaft 3 the housing 11 and the escapement wheel 12 are arranged in the same manner as described in my companion application. A collar 13 on the shaft 3 holds the escapement wheel 12 and is provided with a beveled end extending into the ring 5 and forming, in connection with said ring 5, a race-way for the balls 14 constituting the bearing for this end of the shaft 3. The rocker 15, the stationary pawl 16 and the pivoted pawl 17 are arranged substantially the same as described in my companion application. In the present instance the rocker 15 has ball bearings 18 holding them upon their supports 19. The pawl 16, it will be remembered, is mounted on a pivot pin 16^a and is movable on said pivot pin from one side to the other side of the pivoted pawl 17 as required for regular or speed escapement, and is held in its different adjustments by locking pin 16^b mounted in a hole in the rocker and actuated against the pawl 16 by a leaf spring 16^c; said pin constituting means for holding the pawl in its different adjustments.

To the lower arm of the hanger or support 1 a curved stop member 20 is pivoted and is provided with two arms extending toward the rocker 15, said rocker being provided with a lower arm 21 for contact with the lower arm of the stop member. Abutment pads 22 are attached to the rocker for contact with the arms of the stop member when the rocker is operated. A spring 23 connects the upper arm of the stop member 20 to the rocker 15, thereby holding said parts in the position shown in Fig. 2. A screw 24 operates through an extension 25 on the stop member 20, and is provided on its inner end with a flanged member 26 which rests in a notch in a projection 27 on the hanger 1. By adjustment of the screw 24 the stop member 20 may be moved to any desired position as required for operation of the pawls in speed or regular escapement.

In Fig. 2 wherein the movable pawl 17 is shown in engagement with the escapement wheel 12, the escapement is adjusted for regular escapement. For speed escapement

the pawl 16 is moved to the other side of the pawl 17, occupying with respect to said pawl 17 the position shown by dotted lines in Fig. 2. The pawls having been adjusted 5 in this manner, the screw 24 is operated to move the stop member 20 to the position indicated by dotted lines, which operation swings the rocker 15 to position to hold the movable pawl 17 out of engagement with the escapement wheel and the stationary pawl 16 in its new adjustment in engagement 10 with said escapement wheel. Oscillation of the rocker 15 is effected by suitable connections leading to the operating 15 mechanism.

I am aware that there may be modifications and alterations in the construction and arrangement of the parts embodying this invention without departure from the spirit 20 and scope of the invention, and I do not restrict myself to identical features of construction or arrangement, but

What I claim and desire to secure by Letters Patent, is

25 1. In an escapement mechanism, the combination with the escapement wheel, pawls movable across said wheel, and means for holding said pawls in different positions with respect to each other, of a single stop member limiting movement of the pawls, and an element adjustable to hold said stop member in different positions corresponding to the position in which the pawls are adjusted with respect to each other, substantially 30 as specified.

35 2. In an escapement mechanism the combination with an escapement shaft and ball bearings supporting the same, an escapement wheel mounted on said shaft, a rocker, and pawls mounted in said rocker and arranged to engage with escapement wheel, of means for holding said pawls in different adjustments with respect to each other as required to effect speed and regular escapement of a stop member, and an adjustable device for holding said stop member in different adjustments corresponding to the different adjustments of the pawls with respect to each other, substantially as specified.

40 3. In an escapement mechanism, the combination with an escapement wheel, a rocker, pawls carried by said rocker arranged to engage with said escapement wheel and adjustable with respect to each other for speed and regular escapement, of a stop member arranged to stop movement of said pawls in both directions during their operation, and a device operable to adjust and hold 45 said stop member in different positions corresponding to the adjustment of the pawls

with respect to each other, substantially as specified.

4. In an escapement mechanism, the combination with an escapement wheel, a rocker, two pawls carried by said rocker and arranged to engage alternately with said escapement wheel during operation, and means for locking one of said pawls in different positions as required for speed and 65 regular escapement, of a stop for limiting movement of said pawls during their operation, and a device for adjusting said stop to correspond with the adjustment of said pawls, substantially as specified. 70

5. In an escapement mechanism, the combination with the pawl rocker, of a stop member for said pawl rocker, a spring connecting said stop member with said rocker, and a device for holding said stop member 80 in different adjustments.

6. In an escapement mechanism, the combination with a support, and a pawl rocker in said support, of a stop member limiting movement of said rocker in both directions, 85 a spring connecting said rocker with said stop member, and means acting against said support effectively to hold said stop member in any desired adjustment, substantially as specified. 90

7. In an escapement mechanism, the combination with an escapement wheel, a rocker, two pawls carried by said rocker and arranged to engage alternately with said wheel during operation, of a stop limiting 95 movement of said pawls during their operation, means for adjusting and holding said stop in different adjustments effectively to permit operation of said pawls in speed or regular escapement as desired, and a 100 spring actuating said pawls to idle position, substantially as specified.

8. In an escapement mechanism, the combination with a support, a rocker extending above and below said support, pawls carried 105 by said rocker, a stop member extending above and below said support and being effective to limit movement of said rocker in both directions, a device for adjusting and holding said stop member in different adjustments, and a spring connecting said rocker with said stop member, substantially as specified. 110

In testimony whereof, I hereunto affix my signature to this specification this 16th day 115 of January, 1909, in the presence of two witnesses.

JOSEPH RABER. [L. S.]
